United States Patent Office

Des. 221,769
Patented Sept. 7, 1971

221,769

PORTABLE SHOWER

George T. Le Blanc and Clifford H. Le Blanc, both of P.O. Box 1914, Beaumont, Tex. 77704, and Thomas A. Balmer, and Bobbie G. Hurst, Beaumont, Tex.; said Balmer and said Hurst assignors to George T. Le Blanc and Clifford H. Le Blanc

Filed May 15, 1970, Ser. No. 23,000

Term of patent 14 years

Int. Cl. D23—02

U.S. Cl. D23—57

FIG. 1 is a perspective view of a portable shower showing our new design; and

FIG. 2 is another perspective view thereof, with the shower curtain omitted for convenience of illustration.

We claim:

The ornamental design for portable shower, as shown and described.
